US00D918466S

(12) **United States Design Patent** (10) Patent No.: **US D918,466 S**
(45) Date of Patent: ** May 4, 2021

(54) **VAPORIZING DEVICE**

(71) Applicant: **NJOY, LLC**, Scottsdale, AZ (US)

(72) Inventor: **Simon Yan**, New York, NY (US)

(73) Assignee: **NJOY, LLC**, Scottsdale, AZ (US)

(**) Term: **15 Years**

(21) Appl. No.: **29/694,801**

(22) Filed: **Jun. 13, 2019**

(51) LOC (13) Cl. **27-02**

(52) U.S. Cl.

USPC **D27/162**

(58) **Field of Classification Search**

USPC D27/162, 100, 101, 163–165, 172,

D27/174–176, 183, 185–194; D24/110,

D24/110.5; D23/366

CPC A24F 47/002; A24F 47/006; A24F 47/008;

A61M 15/00; A61M 15/06

See application file for complete search history.

(57) **CLAIM**

The ornamental design for a vaporizing device, as shown as described.

DESCRIPTION

FIG. 1 is a perspective view of the vaporizing device;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Features shown in broken lines form no part of the design as claimed.

1 Claim, 4 Drawing Sheets
